TABLE

Harold Rubin, Berwyn, Ill.

Application May 17, 1956, Serial No. 41,529

Term of patent 14 years

(Cl. D33—14)

I claim:

The ornamental design for a table, substantially as shown.
